AUTOMATIC FREQUENCY CONTROL
SYSTEMGarrard Mountjoy, Manhasset, N. Y., assignor to
Radio Corporation of America, a corporation
of Delaware

Application April 12, 1938, Serial No. 201,500

8 Claims. (Cl. 250—20)

My present invention relates to receivers of the type employing automatic frequency control (AFC), and more particularly to such a receiver embodying a novel control mechanism for the 5 AFC.

Receivers of the AFC type often utilize a plurality of cascaded resonant circuits to feed the audio detector, while the discriminator rectifiers are connected to an intermediate one of the cascaded circuits. When such a receiver is of the multi-range type as well, and AFC action is desired only on less than all the wave bands, it is necessary to use a mechanism for eliminating the AFC action over the frequency range where it 10 is not desired. Mere opening, or short-circuiting, of the AFC lead to the frequency control tube is not adequate; such expedient in no way improves the reception characteristic. For example, an improvement in the selectivity characteristic 15 is desirable when the AFC has been eliminated.

It may be stated that it is one of the main objects of my present invention to provide in an AFC receiver of the type employing cascaded resonant discriminator and audio demodulator circuits, a device for substantially reducing the impedance loading of the discriminator resonant input circuit when the AFC action is rendered ineffective over a desired frequency range thereby substantially to improve the selectivity to the 20 audio demodulator.

Another important object of my invention may be stated to reside in the provision of a multi-band receiver provided with AFC; means being 25 provided to act jointly with the wave band changing mechanism to render the AFC ineffective over at least one of the reception bands and simultaneously to improve the selectivity to the audio demodulator.

Still other objects of the invention are to improve generally the operation of AFC receivers of the multi-band type, and more especially to provide such receivers in an economical manner.

Referring now to the accompanying drawing, there is shown therein a well known type of superheterodyne receiver employing AFC. For example, the receiver may be of the type disclosed, and claimed, by D. E. Foster in application Serial No. 72,495, filed April 3, 1936, patented 45 June 21, 1938, as U. S. P. 2,120,974. Such a receiver comprises a signal collector A feeding the tunable selector circuit 1 of a radio frequency amplifier 2; the amplified modulated carrier signals are impressed on the tunable selector circuit 3 of the first detector 4. The local oscillator 5 is

provided with a tunable tank circuit 6. The dotted lines denoted "Tuner" show the mechanical uni-control coupling between the rotors of the variable tuning condensers of circuits 1—3—6. The local oscillator tank circuit 6 is tunable over a frequency range which differs at all times from the frequency range of the signal selector circuits 1 and 3 by the value of the intermediate frequency; say, for example, 400 kc.

The I. F. energy is transmitted through I. F. 10 amplifiers 7—7'; each of the latter is fixedly resonated to the operating I. F. The I. F.-tuned output circuit 8 of the I. F. amplifier 7' is coupled to a discriminator input circuit 9; the symbol M designates the magnetic coupling between 15 the circuits 8 and 9. The construction of the discriminator follows the disclosure of the aforesaid Foster patent. Briefly, the network comprises diodes 10 and 11; load resistors 12 and 13 being connected in series between the cathodes 20 of the diodes, and the cathode of diode 11 being grounded. The I. F. by-pass condenser 14 is connected across the load resistors; the junction 15 of the latter is connected by lead 21 to the midpoint 16 of the secondary coil 9'. The direct 25 current blocking condenser 17 connects the high potential side of the primary circuit 8 to midpoint 16.

The switch mechanism 20 is disposed in the lead 21. When the switch 20 is open, the discriminator is ineffective to produce AFC bias. The audio demodulator comprises the input circuit 30 arranged in series with diode 31 and load resistor 32. The circuit 30 is magnetically coupled, as at M₁, to circuit 9. The cathode of diode 35 31 is at ground potential, while load resistor 32 is by-passed for I. F. current by condenser 33. The direct current voltage component of detected I. F. current is used for AVC action. The line 34, including a filter 35, acts as the AVC connection to 40 the I. F. amplifier, and to any of the prior tubes when desired. The audio voltage across load resistor 32 is transmitted, by path 40, to a desired audio network.

The discriminator functions, as is now well 45 known by those skilled in the art, to provide across resistors 12 and 13 in series, a direct current voltage (AFC bias) whose polarity and magnitude are dependent upon the direction and amount of frequency shift, respectively, of the 50 I. F. carrier from the assigned I. F. value. Each of circuits 8 and 9 is tuned to the assigned I. F. value; as is, also, the resonant circuit 30. As is explained fully in the aforesaid Foster patent, the selectivity at the audio detector 31 is high 55

- by virtue of the fact that circuits 8—9—30 are in cascade. Instead of taking audio voltage from point 15, extra selectivity is secured by adding the network 30—31.
- 5 The AFC bias, developed between the cathode end of resistor 12 and ground, is impressed upon the frequency control tube 50 by means of the line 51. The latter is designated by the symbol "AFC"; and includes a filter 52 for suppressing pulsation components in the AFC bias. The tube 50 may have its circuits arranged in any manner well known to those skilled in the art; the function of the tube is to simulate across tank circuit 6 a reactance, and the latter may be positive or negative in sign. Reference is made to the application of C. Travis, Serial No. 19,563, filed May 3, 1935, for various types of circuits which may be used at 50. The AFC bias varies the gain of tube 50 in a sense such that the simulated reactance, across tank 6, adjusts the latter in frequency to maintain the assigned I. F. value at the output of network 4. It is not believed necessary to explain the operation of the system up to this point in any further detail.
- 10 The present invention is independent of the particular construction of the discriminator; what is important is that the functioning of the discriminator can be prevented with improved selectivity to the detector 31 secured.
- 15 25 Without going into a detailed explanation, then, of the AFC system, and reference being made again for that purpose to the said Foster patent, it will be understood that as the receiver is tuned by the "tuner" the AFC acts to adjust the oscillator tank 6 so as to secure the correct I. F. value. For example, if the tuning mechanism has been adjusted to receive a desired carrier, but is not accurately set thereto, the local oscillations will beat with the desired signals to produce I. F. energy whose carrier differs from the resonant frequency of circuits 8—9. The carrier shift is translated into a direct current voltage across 12—13; when the carrier is equal to the assigned I. F. value, then the drop across 40 45 50 55 60 65 70 75 12—13 is zero. It is assumed that the switch 20 is closed; this permits each of the rectifiers 10 and 11 to rectify the sum of the voltage across circuit 8 and the voltage induced across one half of the secondary coil 9'. The phase relation between the voltages induced across the two halves of coil 9' depends upon the frequency of the applied I. F. energy. Hence, it will be seen that the diodes 10 and 11, and load resistors 12, 13, comprise a load upon the input circuit 9.
- 80 The AFC bias across resistors 12 and 13 is used to vary the gain of tube 50. The reactance simulated by tube 50 is, therefore, varied; the variation is such as to adjust the frequency of tank circuit 6 to a value which finally results in I. F. energy of the assigned carrier value. The lead 51 could be opened, or short-circuited, to render ineffective the AFC action. However, the loading of the input circuit 9 would still exist, and hence the selectivity to the detector 31 would be impaired to that extent.
- 85 By providing the switch 20 in the lead 21, the loading of circuit 9 can be diminished by opening the switch. With the switch 20 open, the selectivity at the detector 31 is greatly increased.
- 90 70 This is a desirable characteristic, since when the AFC is rendered inoperative the receiver should be as selective as possible. When the receiver is of the multi-range type, the arrangement is of particular value. The circuits 1, 3 and 6 are shown provided with band changing devices 1—

3'—6'. The devices are conventionally represented; those skilled in the art are fully acquainted with the construction thereof. The dotted lines 60 denote the uni-control device coupling the adjustable taps of the changing devices. The taps are shown arranged for three successive bands. The dotted line 61, between switch element 20 and the band changing device 60, denotes a mechanism for automatically opening switch 20 when the device 60 is adjusted to select a range of signal carrier frequencies over which AFC action is not desired.

95 Of course, the device 60 and switch 20 can be correlated so that switch 20 will be opened alternately with adjustments to the taps of devices 15 1'—3'—6'. Also, any desired relation between the two devices may be used. In this way there is provided a mechanism for rendering the AFC action inoperative while simultaneously improving the selectivity to the audio detector; further, the mechanism is employed, where the receiver is of the multi-band type, to cut out the AFC action with selectivity improvement on those bands where the AFC is not desired.

100 While I have indicated and described one system for carrying my invention into effect, it will be apparent to one skilled in the art that my invention is by no means limited to the particular organization shown and described, but that many modifications may be made without departing from the scope of my invention, as set forth in the appended claims.

105 What I claim is:

1. In combination with at least two cascaded coupled resonant circuits tuned to the same carrier frequency, a source of carrier waves coupled to the first of the circuits, a detector coupled to the second of the circuits, means coupled to the said first circuit for deriving a direct current voltage therefrom which is dependent in magnitude and polarity upon the carrier frequency departure, said deriving means normally loading said first circuit, and switch means operatively associated with said first circuit and deriving means for removing the loading effect of the latter thereby to decrease the said first circuit loading and increase the selectivity to said detector.

110 2. In combination with at least two cascaded coupled resonant circuits tuned to the same carrier frequency, a source of carrier waves coupled to the first of the circuits, a detector coupled to the second of the circuits, means coupled to the said first circuit for deriving a direct current voltage therefrom which is dependent in magnitude and polarity upon the carrier frequency departure, said deriving means normally loading said first circuit, and switch means operatively associated with said first circuit and deriving means for removing the loading effect of the latter thereby to decrease the said first circuit loading and increase the selectivity to said detector, and an oscillator network, electrically associated with said wave source, having a frequency adjusting connection to said deriving means.

115 3. In combination with at least two cascaded coupled resonant circuits tuned to the same carrier frequency, a source of carrier waves coupled to the first of the circuits, a detector coupled to the second of the circuits, means coupled to the said first circuit for deriving a direct current voltage therefrom which is dependent in magnitude and polarity upon the carrier frequency departure, and means for rendering said deriving means ineffective thereby to decrease the said

- first circuit loading and increase the selectivity to said detector, said deriving means comprising opposed rectifiers, and said last means including a switch connected in the common return path 5 from said first circuit to the two rectifiers.
4. In a superheterodyne receiver, an intermediate frequency transmission network having a resonant output circuit, a second resonant circuit, tuned to the intermediate frequency, coupled to the first circuit, a pair of opposed rectifiers with a common resistive load coupled to the second circuit and normally loading it, a third resonant circuit, tuned to said frequency, coupled to the second circuit, a demodulator coupled to the 10 third circuit, and switch means operatively associated with the second circuit and rectifiers for reducing the loading effect of said opposed rectifiers and resistive load thereby to increase the selectivity at the demodulator.
- 10 5. In a superheterodyne receiver, an intermediate frequency transmission network having a resonant output circuit, a second resonant circuit, tuned to the intermediate frequency, coupled to the first circuit, a pair of opposed rectifiers with a common resistive load coupled to the second circuit and normally loading it, a third resonant circuit, tuned to said frequency, coupled to the second circuit, a demodulator coupled to the third circuit, and means for reducing 15 the loading effect of said opposed rectifiers and resistive load thereby to increase the selectivity at the demodulator, said reducing means including a switch device connected between the midpoint of the second circuit and the midpoint of the resistive load.
- 20 6. In a superheterodyne receiver, an intermediate frequency transmission network having a resonant output circuit, a second resonant circuit, tuned to the intermediate frequency, coupled to the first circuit, a pair of opposed rectifiers with a common resistive load coupled to the second circuit and normally loading it, a third resonant circuit, tuned to said frequency, coupled to the second circuit, a demodulator coupled 25 to the third circuit, and adjustable means solely operatively associated with the second circuit and said rectifiers for reducing the loading effect of said opposed rectifiers and resistive load thereby to increase the selectivity at the demodulator, a local oscillator having a tunable tank network, a frequency control tube connected to the tank network and having a connection to the resistive load.
- 25 7. In a multi-wave band receiver, signal and oscillator networks, means for selecting the wave band for reception by the receiver, a discriminator having a beat frequency input circuit for producing a voltage dependent solely upon a received carrier frequency shift, a demodulator having a beat frequency input circuit coupled in cascade with said discriminator input circuit, means utilizing said voltage to adjust the oscillator frequency, and means, conjointly operative with the band selecting means, for simultaneously impairing the operation of the discriminator and increasing the selectivity to the demodulator when selecting a wave band over which the oscillator adjusting means is to be ineffective.
- 30 8. In a multi-wave band receiver, signal and oscillator networks, means for selecting the wave band for reception by the receiver, a discriminator having a beat frequency input circuit for producing a voltage dependent solely upon a received carrier frequency shift, a demodulator having a beat frequency input circuit coupled in cascade with said discriminator input circuit, means utilizing said voltage to adjust the oscillator frequency, and additional means, conjointly operative with the band selecting means, for simultaneously impairing the operation of the discriminator and increasing the selectivity to the demodulator when selecting a wave band over which the oscillator adjusting means is to be ineffective, said additional means comprising a device operatively associated with the discriminator for preventing production of said voltage.

GARRARD MOUNTJOY.
